DESIGN.

I. H. ISAACS.

BED.

APPLICATION FILED JULY 24, 1920.

56,725.

Patented Dec. 7, 1920.

Irving H. Isaacs, Inventor,

By his Attorney,

W. B. Hutchinson.

UNITED STATES PATENT OFFICE.

IRVING H. ISAACS, OF NEW YORK, N. Y.

DESIGN FOR A BED.

56,725.

Specification for Design.

Patented Dec. 7, 1920.

Application filed July 24, 1920. Serial No. 398,823. Term of patent 14 years.

To all whom it may concern:

Be it known that I, IRVING H. ISAACS, a citizen of the United States, and a resident of the city, county, and State of New York, have invented a new, original, and ornamental Design for Beds, of which the following is a specification, reference being had to the accompanying drawing, forming a part thereof.

The figure is a perspective view of the bed showing my design.

I claim:

The ornamental design for a bed as shown.

IRVING H. ISAACS.

Witnesses:

SAMUEL AKRONMAN,
FLORA KRAMER.
